LPA(57) **CLAIM**

The ornamental design for a step as shown and described.

DESCRIPTION

FIG. 1 is a perspective top front right view of a step, showing my new design;
 FIG. 2 is a perspective bottom rear right view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines depict portions of the step that form no part of the claimed design.
